Attorney

UNITED STATES PATENT OFFICE.

ALBERT ULCH, OF CHELSEA, IOWA.

HAY-UNLOADING APPARATUS.

1,182,119.

Specification of Letters Patent. Patented May 9, 1916.

Application filed February 11, 1916. Serial No. 77,743.

To all whom it may concern:

Be it known that I, ALBERT ULCH, a citizen of the United States, residing at Chelsea, in the county of Tama and State 5 of Iowa, have invented certain new and useful Improvements in Hay-Unloading Apparatus, of which the following is a specification, reference being had to the accompanying drawings.

10 This invention relates to an improved hay unloading apparatus and has for its primary object to provide means which may be operated and controlled by one man for expeditiously unloading hay from a rack and 15 storing the same in a barn.

The invention has for another object to provide a carrier mounted to travel longitudinally upon a track extending longitudinally into the barn, a hay fork carried by 20 said carrier, a weight-actuated cable connected to the carrier to move the same into the barn, a gear-operated drum, and cables connected to the drum and to the controlling weight and adapted to raise and lower the 25 weight when the drum is rotated in reverse directions.

It is a further object of the invention to provide an apparatus for the above purpose, which is simple in its construction, highly 30 serviceable and convenient in practical use, and may be manufactured and installed at relatively small cost.

With the above and other objects in view, my invention consists in the novel features 35 of construction, combination and arrangement of parts to be hereinafter more fully described, claimed and illustrated in the accompanying drawings, in which,

Figure 1 is a side elevation of my improved hay unloading apparatus showing the carriage in its discharge position within the barn; Fig. 2 is a similar view, the carriage being disposed exteriorly of the barn in its load receiving position; Fig. 3 is an 45 elevation on an enlarged scale of the weighted cable pulleys, illustrating the connections of the cables; Fig. 4 is a side elevation of the drum operating gearing; and Fig. 5 is a top plan view thereof.

50 Referring in detail to the drawings, 5 designates a longitudinally extending track

which is suitably mounted in the top of the barn and at one of its ends extends exteriorly thereof. Upon this track, the traveling carriage 6 is arranged and is provided with a hay fork indicated at 7. The track, carriage and fork may be of any ordinary or approved construction, said fork being equipped with the usual trip device whereby its load may be released. 8 indicates the cord extending from the trip device, whereby the same may be actuated. Upon the inner end of the elevated track 5, a pulley or sheave 9 is suitably mounted, and a second pulley or sheave 10 is also supported by the track adjacent to the pulley 9.

11 indicates a suitable yoke or frame in which a pair of pulleys 12 are rotatably mounted, the axes of said pulleys being in vertical alinement. To the lower end of 70 this yoke frame, suitable weights 13 are fixed, and between these weights an additional pulley 14 is mounted in bearing arms 15 depending from the frame 12. In a suitable support 16 fixed to the floor or other 75 suitable stationary part of the barn structure, a pair of pulleys 17 are rotatably mounted. One end of a rope or cable 18 is attached to a bail 19 depending from the axis of the pulley 14. This cable is carried 80 downwardly around the uppermost pulley 17 and then upwardly around the pulley 14 and again downwardly and around the lower pulley 16. From this lower pulley, the cable 18 is extended around suitable 85 guide pulleys indicated at 20, and attached to one section of a double drum shown at 21 which is suitably mounted upon the forward end wall of the barn. The operating means for this drum will be hereinafter described. 90 A cable 22 is also attached at one of its ends to the other section of the drum 21 and passes around a guide pulley 23 and then rearwardly over the guide pulley 9, said cable extending downwardly from this 95 guide pulley and around the lowermost pulley 12 and then upwardly around the pulley 10, and from the pulley 10 the cable extends downwardly around the upper pulley 12 and again upwardly, and is fixed at its 100 end to a bail or loop indicated at 24. A second cable 25 is also attached to this bail.

and extends downwardly around the upper pulley 12 and then upwardly over the pulley 10 and against downwardly and around the lower pulley 12 and upwardly over the pulley 9. This cable is extended from the latter pulley over a pulley 26 mounted on the carriage 6 and under a sheave 27 from which the hay fork is suspended, the end of the cable being suitably secured to one end of the carriage. A cable 28 is also attached to the forward end of the carriage 6 and extends exteriorly of the barn over a supporting sheave 29 mounted on the extended end of the track 5. To the end of this cable, a sheave 30 is attached, said sheave being provided with a weight 31. This sheave moves upon a guide cable 32 which is adapted to be extended directly outwardly from the end of the track 5 and suitably anchored at its lower end. Upon the shaft of the drum 21, a pinion 33 is fixed, and with the same a manually operable gear 34 meshes, said gear having a crank handle 35.

36 designates guide loops for the cables which are wound upon the drum sections, and it will be noted that the cable which is connected to the weighted pulley block extends around its drum section in one direction while the other cable 22 extends around the other drum section in a relatively opposite direction. It will thus be apparent that when one of the cables is unwound from the drum, the other cable is wound thereon.

35 In the operation of the device, it will be understood that the weighted pulley carrying block to which the cable 24 is connected, normally tends to pull the carriage inwardly to the inner end of the track 5. Assuming 40 that the hay fork has been supplied with a load of hay, the operator, upon turning the crank of the gear 34 to the right, rotates the drum so that the cable 22 will be wound thereon, thus pulling the weighted pulley block downwardly and the other cable 24 will be permitted to unwind from the pulley, and the pulley block moves downwardly. Of course, the carriage carrying the load of 45 hay is moved inwardly to the lower end of the track frame. The trip cord connected to the trip device of the hay fork is then pulled to release the load. Upon reversing the rotation of the gear 34, the cable 22 will unwind from the drum while the cable 24 will 50 be wound thereon, thus elevating the pulley block. The weighted pulley 30 on the end of the cable 28 will thus move downwardly upon the guide cord or cable 32 and the carriage and hay fork will be moved outwardly 55 along the track 5 into position to receive another load of hay. In this manner, it will be seen that the device may be operated entirely by one man, and the contents of the hay rack easily and quickly loaded into a 60 barn.

From the foregoing description, taken in connection with the accompanying drawings, the construction, manner of operation and several advantages of the invention will be fully understood. The member indicated at 70 37, fixed to the under side of the track at its outer end, is for the purpose of operating the latch device which holds the hay fork in connection with the carriage so that the hay fork may be pulled downwardly in position to receive the load. 75

It will be appreciated that the apparatus as a whole is comparatively simple in its construction and can be readily installed in an ordinary barn at nominal cost. It will 80 be apparent that the several operating parts of the apparatus may be otherwise mounted and arranged than as above referred to, and the detail structural features of these parts may be variously modified and I, therefore, 85 reserve the privilege of adopting all such legitimate changes as will fairly fall within the spirit and scope of the invention as claimed.

Having thus fully described my invention, 90 what I desire to claim and secure by Letters Patent is:—

1. In a hay unloading apparatus, the combination of a track extending interiorly and exteriorly of a barn, a carriage to travel 95 upon said track, a pair of weighted pulleys, cables passing around said pulleys, guides for the cables, one of said cables being connected to the carriage, a manually operable drum, the other of the cables being attached 100 to the drum to be wound thereon, an additional cable connected to the weighted pulleys at one of its ends and also attached to the drum to wind thereon in an opposite direction with respect to the first named 105 pulley, and means for manually rotating the drum in either direction to raise or lower the weighted pulleys and permit the carriage to travel in either direction upon the track.

2. In a hay unloading apparatus, an elevated track, a hay carriage to travel thereon, gravity means operatively connected to the carriage to move the same in one direction on the track, manually operable means for elevating said gravity means, a weighted 110 pulley and a cable connecting the same to the carriage to move said carriage in an opposite direction with respect to its movement in the descent of said gravity means, and means for guiding the movement of said weighted 115 pulley.

3. In a hay unloading apparatus, an elevated track, a hay carriage to travel thereon, gravity movable means operatively connected to the carriage to move the same in 125 one direction, manually operable means including a reversible drum and cables winding thereon from opposite directions, one of the cables being connected to said gravity means to elevate the same and the other of 130

the cables being connected to said gravity means to lower the same, and gravity movable means operatively connected to the forward end of the carriage to move the same 5 in one direction upon a track when said first named gravity means is elevated.

In testimony whereof I hereunto affix my signature in the presence of two witnesses.

ALBERT ULCH.
